It is known to deposit zirconium dioxide, ZrO_2 , on a substrate comprising a chip or wafer by providing zirconium oxychloride, $ZrOCl_2$, vapor at about $550^\circ C$, the chip or wafer being at $450^\circ C$, in an atmosphere containing water vapor. Zirconium dioxide, ZrO_2 , and hydrochloric acid, HCl, are produced and a layer of the ZrO_2 is deposited on the chip. The ZrO_2 layer acts as a passivation material having high resistivity and very good impermeability to sodium which can be destructive of the circuit on the chip or wafer. According to this invention, the ZrO_2 may be deposited on a substrate at a lower temperature from a liquid solution of the zirconium oxychloride, whereby the substrate may be paper or plastic and whereby the substrate if it includes a circuit will not be injured by the temperature needed by the prior art high temperature treatment, and therefore the possible injury to the substrate or to the circuit therein by the prior art high temperature treatment is avoided.

LIQUID PHASE DEPOSITION OF THIN
INSULATING AND REFRACATORY FILM ON A
SUBSTRATE

BACKGROUND

This is a continuation in part of Ser. No. 99,969, filed Dec. 21, 1970 now abandoned.

The invention relates to deposition on a base or substrate material of a film or layer of zirconium dioxide, ZrO_2 .

A thin layer of zirconium dioxide, ZrO_2 , has high resistance, not quite as high as the resistance of the thin layer of SiO_2 , but considerably higher than the resistance of a thin layer of silicon nitride, Si_3N_4 . Furthermore, zirconium dioxide is much more impermeable to sodium ions, which can cause instabilities in semiconductor devices, than silicon dioxide and it is as impermeable to sodium ions as is silicon nitride. Therefore, a thin layer of zirconium dioxide is a good passivation material for semiconductive devices. A preferred form of semiconductive device is a monocrystalline silicon wafer within which active and passive devices have been formed.

A high temperature method is known for depositing a zirconium dioxide film or layer on a substrate from a vapor phase of zirconium oxychloride, $ZrOCl_2$. The $ZrOCl_2$ is held at about $550^\circ C$, the substrate being held about $450^\circ C$ in a water vapor atmosphere, producing zirconium dioxide which deposits on the substrate, HCl vapor also being evolved. The high temperatures involved in this process may injure the substrate or circuit element deposited thereon. Furthermore, the known process is very critical in that it is difficult to cause it to operate in a desired manner.

It is an object of this invention to provide an improved method of depositing zirconium dioxide on a substrate.

It is a further object of this invention to provide a method of depositing zirconium dioxide on a substrate that involves lower temperatures than the known method.

It is a still further object of this invention to provide a method of depositing zirconium dioxide on a monocrystalline silicon wafer at temperatures within the range of 125° to $250^\circ C$.

SUMMARY

In accordance with the invention, a solution of zirconium oxychloride comprising $ZrOCl_2 \cdot 8H_2O$ in water is put on a substrate to be coated and the water which may be at room temperature is driven off as by spinning or mild heating or both. The Hydrated water is driven off by the heating and the $ZrOCl_2$ which remains is converted to ZrO_2 in one or two steps, leaving a coating or layer or film of ZrO_2 on the substrate. If commercial $ZrOCl_2$ is used, the impure film of ZrO_2 on the substrate which results may act as a voltage responsive switch. If it is desired to add successive layers of ZrO_2 on the first layer thereof, the film may be cleaned by argon plasma cleaning and the process of deposition may be repeated.

DESCRIPTION

The invention will be better understood upon reading the following description together with the accompanying drawing which illustrates steps of the inventive method.

In accordance with the invention, up to about 1 gram of $ZrOCl_2 \cdot 8H_2O$ is dissolved in 9 milliliters of water to produce the plating mixture 10. The mixture is put on the surface of the substrate to be coated and the substrate is spun in a known manner to cover the surface of the substrate, as indicated by the rectangle 12. The spinning of materials onto wafers is well known in the semiconductor processing art. A preferred form of wafer is a monocrystalline wafer or chip. The solution 10 can also be applied by spraying, dipping or by other methods. The spinning on of the mixture gives a uniform coating of the mixture over the surface of the substrate to be coated. To assist in wetting the surface of the substrate, a small amount of a low boiling point alcohol such as ethanol may be added to the solution before it is put on the substrate or the substrate may be cleaned as by argon plasma cleaning before the solution is put thereon or both techniques may be used.

At this point two alternative continuations of the disclosed method appear. According to the first alternative, the substrate, with the solution thereon, is heated in the range of 125° – $250^\circ C$ to drive off the hydrated water and leave a solid layer of $ZrOCl_2$ on the substrate. Then, the heating is continued at a temperature between $125^\circ C$ to about $250^\circ C$ in an atmosphere containing water vapor and the $ZrOCl_2$ becomes ZrO_2 through a chemical reaction with the HCl being driven off. According to the second alternative, the substrate is heated in the range of 125° – $250^\circ C$ in a dry atmosphere and the $ZrOCl_2$ on the chip becomes ZrO_2 through a chemical reaction with HCl being driven off. With either method a highly resistive ZrO_2 coating that is highly impermeable to sodium ions is produced on the substrate.

As noted above, the addition of the low boiling point alcohol and the argon plasma cleaning of the substrate surface for the production of the first layer of ZrO_2 is optional. The coating action takes place without the ethanol or the argon plasma cleaning, however the use of ethanol and the cleaning or either thereof results in better coverage of the substrate.

It has been found that upon using commercially pure $ZrOCl_2$, the produced film may have impurities such as chlorine therein. The film may act as a voltage responsive switch in that, if a high voltage is applied across the otherwise highly resistive film, the resistance of the film drops greatly. Such films have been baked up to $900^\circ C$ to densify them but the switching property persists.

A single layer of ZrO_2 may be about 500 to 1,000 angstrom units thick. This layer may be thick enough to produce the voltage responsive switch but not thick enough to act as a passivation layer. If it is desired to build up several layers of ZrO_2 , the previous layers are cleaned using the known argon plasma method. Then the deposition process is repeated for each additional layer of ZrO_2 . As many layers of ZrO_2 may be produced in this manner as is desired.

It has been found that if more than about 1 gram of $ZrOCl_2 \cdot 8H_2O$ is dissolved in about 9 milliliters of H_2O , the ZrO_2 film is not formed by the method disclosed above in that the ZrO_2 is deposited as separate, thick, crystalline patches on the substrate.

What is claimed is:

1. A low temperature method of depositing a layer of ZrO_2 on a surface, comprising the steps of:
providing a substrate having a surface to be coated with ZrO_2 ;

spreading a mixture of up to substantially 1 gram $\text{ZrOCl}_2 \cdot 8\text{H}_2\text{O}$ dissolved in substantially 9 milliliters of water on said surface to uniformly coat the surface as desired; and

heating the coated substrate to a temperature within the range of 125°C to about 250°C until the hydrated water of the $\text{ZrOCl}_2 \cdot 8\text{H}_2\text{O}$ is driven off and the ZrOCl_2 has changed to ZrO_2 .

2. The method of claim 1 and further including the step of:

adding ethanol to the mixture for increasing the wetting of the mixture with the surface of the substrate.

3. The method of claim 1 and further including the step of:

cleaning the surface of the substrate with argon plasma prior to spreading the mixture on the surface.

4. The method of claim 1 and further including the step of:

cleaning the deposited layer of ZrO_2 with argon plasma; and

repeating the steps to form a second layer of ZrO_2 .

5. The method of claim 1 wherein said heating step further comprises:

heating said coated substrate to a temperature lying within the range of 125°C to about 250°C in a dry atmosphere for driving the water of hydration out of the $\text{ZrOCl}_2 \cdot 8\text{H}_2\text{O}$ and to change the ZrOCl_2 to ZrO_2 .

6. The method of claim 5 and further including the step of:

cleaning the deposited layer of ZrO_2 by argon plasma cleaning; and

repeating the steps to form a second layer of ZrO_2 on the cleaned ZrO_2 layer.

7. A low temperature method of depositing a layer of ZrO_2 on a surface, comprising the steps of:

providing a substrate having a surface to be coated with ZrO_2 ;

spreading a mixture of up to substantially 1 gram of $\text{ZrOCl}_2 \cdot 8\text{H}_2\text{O}$ dissolved in substantially 9 milliliters of water on the surface to uniformly coat the surface as desired;

heating the coated substrate to a temperature lying within the range of 125° to 250°C until the hydrated water of $\text{ZrOCl}_2 \cdot 8\text{H}_2\text{O}$ is driven off; and continue heating the coated substrate to a temperature lying within the range of 125° to 250°C in an atmosphere containing water vapor until the ZrOCl_2 has changed to ZrO_2 .

8. The method of claim 7 and further including the step of:

cleaning the deposited layer of ZrO_2 by argon plasma cleaning; and

repeating the steps to form a second layer of ZrO_2 .

9. A low temperature method of depositing a layer of ZrO_2 on a surface comprising the steps of:

providing a silicon substrate having a surface to be coated with ZrO_2 ;

forming a mixture by dissolving up to about 1 gram

of $\text{ZrOCl}_2 \cdot 8\text{H}_2\text{O}$ in about 9 milliliters of water; adding ethanol to the mixture for increasing the wetting of the mixture with the surface of the substrate;

spreading the mixture on the substrate to uniformly coat the surface as desired; and

heating the coated substrate to a temperature within the range of 125°C to about 250°C until the hydrated water of the $\text{ZrOCl}_2 \cdot 8\text{H}_2\text{O}$ is driven off and the ZrOCl_2 has changed to ZrO_2 .

10. The method of claim 1 and further including the step of:

cleaning the surface of the substrate with argon plasma prior to spreading the mixture on the surface.

11. The invention of claim 1 and further including the step of:

cleaning the deposited layer of ZrO_2 with argon plasma; and

repeating the steps to form a second layer of ZrO_2 .

12. A low temperature method of depositing a layer of ZrO_2 on a surface, comprising the steps of:

providing a silicon substrate having a surface to be coated with ZrO_2 ;

forming a mixture by dissolving up to substantially one gram of $\text{ZrOCl}_2 \cdot 8\text{H}_2\text{O}$ in substantially 9 milliliters of water;

adding ethanol to the mixture for increasing the wetting of the mixture with the surface of the substrate;

placing a quantity of the mixture on the silicon substrate and spinning the substrate to uniformly coat the surface as desired;

heating the coated substrate to a temperature lying within the range of 125°C to about 250°C in a dry atmosphere for driving the water of hydration out of the $\text{ZrOCl}_2 \cdot 8\text{H}_2\text{O}$ and for changing the ZrOCl_2 to ZrO_2 .

13. A low temperature method of depositing a layer of ZrO_2 on a surface, comprising the steps of:

providing a silicon substrate having a surface to be coated with ZrO_2 ;

forming a mixture by dissolving up to substantially one gram of $\text{ZrOCl}_2 \cdot 8\text{H}_2\text{O}$ in substantially 9 milliliters of water;

adding ethanol to the mixture for increasing the wetting of the mixture with the surface of the substrate;

placing a quantity of the mixture on the silicon substrate and spinning the substrate to uniformly coat the surface as desired;

heating the coated substrate to a temperature lying within the range of 125° to about 250°C until the hydrated water of the $\text{ZrOCl}_2 \cdot 8\text{H}_2\text{O}$ is driven off; and

continue heating the coated substrate to a temperature lying within the range of 125° to 250°C in an atmosphere containing sufficient water vapor until the ZrOCl_2 has changed to ZrO_2 .
